Primary Examiner — Vy Koenig*Assistant Examiner* — Omeed Agilee(74) *Attorney, Agent, or Firm* — Fenwick & West LLP(57) **CLAIM**

The ornamental design for a camera arm mount, as shown and described.

DESCRIPTION

FIG. 1 is a rear, top, and left perspective view of a camera arm mount;

FIG. 2 is a front, bottom, and right perspective view thereof;

FIG. 3 is a rear, top, and right perspective view thereof;

FIG. 4 is a front, bottom, and left perspective view thereof;

FIG. 5 is a front view thereof;

FIG. 6 is a rear view thereof;

FIG. 7 is a right view thereof;

FIG. 8 is a left view thereof;

FIG. 9 is a top view thereof; and,

FIG. 10 is a bottom view thereof.

The broken lines in the drawings depict portions of the camera arm mount that form no part of the claimed design.
